poration of Delaware

Application December 28, 1932, Serial No. 649,190

1 Claim. (Cl. 250—36)

This invention relates to electronic apparatus for the production of extremely short electromagnetic waves; and to signaling systems embodying such apparatus.

Attempts have been made to produce short wave oscillations by arranging an electronic tube to oscillate through its internal or inherent inter-electrode capacities. One means that has been utilized is to provide between grid and anode electrodes an inductive connection of extremely small inductance value, such as is provided by a short section of uncoiled conductor.

The experiment has in the past met with but dubious success. Production of oscillations has been erratic, undependable, and not reproducible with any degree of uniformity. Of different oscillators constructed of apparently identical parts, some oscillate while others do not. No explanation has heretofore been advanced as to the reasons for this, nor has any certain remedy been proposed.

As a result of theoretical studies, backed by experiment, culminating in the present invention, I am convinced that the difficulties experienced by earlier investigators have resulted from their failure to understand and hence properly satisfy the criteria governing the production of sustained oscillations which are peculiar to the type of oscillator described.

It is a primary object of the present invention to enunciate these criteria to the end that those skilled in the art may with certainty and precision, so arrange electronic apparatus of the character referred to as to assure generation in a reproducible manner, of sustained oscillations having a desired amplitude and frequency.

A further object of the invention is to disclose a high frequency, or short wave, oscillation system adjustable to meet the conditions which are disclosed herein as being requisite to sustained oscillation.

In the drawing:

Fig. 1 shows a short wave communication system embodying an oscillation generator in accordance with the present invention.

Fig. 2 is a diagrammatic showing of the portion of the Fig. 1 circuit which is essential to oscillation production.

The circuit of Fig. 1 employs an electron tube V having an anode or plate P, a filament or cathode K, and a control electrode or grid G. The tube is energized from suitable potential sources applied over conductors 1-4 inclusive extending respectively to the grid, cathode and anode.

Grid conductor 1 includes a high frequency blocking element I₁ and the secondary of a transformer T₁, the primary of which is connected to a modulating element M, such as a microphone transmitter, energized from the source connected to cathode conductors 2-3. Anode conductor 4

contains a blocking element I₂, and the primary of a transformer T₂, the secondary of which is connected to a signal indicating device R, such as a pair of phones. Blocking elements I₃ isolate at high frequency, the cathode K from the potential supply source.

Connected directly between grid G and plate P, is an extremely small variable condenser D₁. For purposes of withdrawing oscillatory energy from or impressing oscillatory energy upon the system, there is provided a tri-plate condenser D₂ having an intermediate stator plate connected to a wave radiator or antenna A, and external plates connected respectively to grid G and plate P. Condensers D₁ and D₂ are of a construction permitting micrometric adjustments of the inter-plate capacities. The plates other than the intermediate stator plate, are preferably annular, with the plate separations adjustable by screw threaded means.

The system of Fig. 1 will upon proper adjustment of the circuit elements indicated as variable, generate sustained oscillations of extremely high frequency. Operation thereafter to transmit and receive signals is apparent from the drawing. On transmitting the amplitude of high frequency oscillations produced by tube V, is varied in correspondence with modulating potentials applied to grid G due to activation of device M. Detection of modulated waves impinging upon antenna A, is effected through curvature of the tube characteristic, the modulating components being indicated by device R.

Limiting consideration to those portions only of the Fig. 1 circuit responsible for the generation of sustained oscillations, the circuit may, at the oscillation frequency, be represented as shown diagrammatically in Fig. 2. At this frequency there is effectively between grid and plate electrodes a small inductance L in series with resistance R. C₂ is the interelectrode capacity between grid and anode of the tube, while C₁ and C₃ are the effective capacities occurring between grid and cathode and between cathode and anode, respectively.

If, referring to the circuit of Fig. 2, the impedances between grid and cathode, grid and anode, and anode and cathode electrodes, respectively, are represented by the generalized vector impedances Z₁, Z₂ and Z₃, it can be shown that the following equality represents the necessary and sufficient condition requisite to the production and maintenance of sustained oscillations:

$$(1) \quad \frac{g}{\mu} \cdot (Z_1 + Z_2 + \mu Z_3) = \frac{1}{Z_3} \cdot (Z_1 + Z_2 + Z_3)$$

where g and μ are respectively the mutual con-

ductance and the magnification factor of the tube.

Inasmuch as the vector impedances Z of Equation (1) in general comprise real and imaginary components the sums of each of which must separately satisfy the condition of equality, it will be seen that Equation (1) is equivalent to a system of two equations determining the frequency f and the value of mutual conductance g at which oscillations can be maintained. It is obvious from the problem that the values for f and g thus derived from the fundamental equation must be real, positive quantities if oscillations are to be sustained. Moreover, the value of the mutual conductance g required must not exceed the maximum mutual conductance g_m of the tube.

Replacement of the generalized impedances of Equation (1) by the specific inter-electrode impedances of Fig. 2 results, neglecting higher order terms in R , in the following expression requisite to the maintenance of oscillations with the circuit of Fig. 2:

$$(2) \quad \frac{C_1}{C_3} = \mu \left[1 - \frac{R_d \cdot g(C_1 C_2 + C_1 C_3 + C_2 C_3)}{\mu^2 C_3^2} \right] \frac{4\pi^2 f^2 R_d (C_1 C_2 + C_1 C_3 + C_2 C_3)}{g}$$

where R_d denotes the dissipative component of the impedance Z_2 at the oscillation frequency.

Examination of Equation (2) shows that under no circumstances can the circuit of Fig. 2 be made to oscillate if the capacity ratio

$$\frac{C_1}{C_3}$$

equals or exceeds the magnification factor μ of the tube. From Equation (2) we therefore derive the result, verified by experiment, and contrary to what has heretofore been understood, that oscillations cannot be maintained with the Fig. 2 type of circuit, even for exceedingly large values of mutual conductance g , unless the capacity ratio

$$\frac{C_1}{C_3}$$

is less than the magnification factor μ of the tube.

Further examination of Equation (2) reveals that for a tube of given constants the maximum capacity ratio

$$\frac{C_1}{C_3}$$

at which oscillations will be sustained depends upon the dissipative resistance of the inductive connection and upon the oscillation frequency. For a given tube, the relationship may for some purposes best be shown by the following inequality derived from Equation (2):

$$(3) \quad \frac{C_1}{C_3} < \mu \cdot (1 - R_d \cdot f^2 \cdot K)$$

where K is a constant dependent upon the internal capacities and mutual conductance of the tube, and f the oscillation frequency in cycles per second. In order therefore for the circuit to sustain oscillations, the capacity ratio

$$\frac{C_1}{C_3}$$

must be less than the magnification factor μ of the tube by an amount which is proportional to

the product of the resistance R_d and the square of the frequency.

From Equation (2) one derives the additional general conclusions that conditions favorable to efficient oscillation production are improved to the extent that the ratio of capacities C_1 to C_3 is decreased below μ . And again that the limiting frequency of oscillation may be increased by increase of the maximum mutual conductance g_m , by decrease of the dissipative resistance R_d , or by a combination of these several factors.

It has generally been thought that tubes best adapted to the production of extremely high frequencies are those wherein the interelectrode tube capacities have been made as small as possible. To this end tubes have been utilized wherein "stray" capacity effects, due to the tube base, etc., are minimized or eliminated as by removing the base, etc. In a sense this, as shown by Equation (2), is a step in the wrong direction since it fixes the ratio of the grid-to-cathode and anode-to-cathode capacities at a relatively high value, determined by the closer spacing between grid and cathode than that extant between anode and cathode. The present invention teaches that "stray" or auxiliary capacities are beneficial to sustained oscillation to the extent that they reduce the capacity ratio in question.

Analysis of the Fig. 1 circuit has shown that for generated waves, say of the order of 100 centimeters, the electronic current is appreciably in phase with the alternating components of the grid and plate voltage provided these voltages are not too small.

The adjustable condensers D_1 and D_2 serially included in the inductive connections between grid and anode, provide a means of making the effective inductance L , Fig. 2, as small as is necessary for production of oscillations of a desired frequency. At the oscillation frequency f the effective inductance L is:

$$(4) \quad L = L' - \frac{1}{4\pi^2 f^2 D}$$

where L' is the actual inductance between grid and plate, and D the effective capacity of condensers D .

Thus condensers D permit of adjusting the oscillation frequency as desired, within limits, while the selection of a proper capacity ratio

$$\frac{C_1}{C_3}$$

assures maintenance of oscillations at that frequency.

I claim:

Device for generating and detecting short electric waves, comprising the combination with an electron tube having an anode, a cathode and a grid, of an inductive connection between said grid and anode, a condenser serially included in said inductive connection for adjusting the generated wave length, the interelectrode capacities between said grid and cathode and between said anode and cathode respectively, having a ratio sufficiently smaller than the magnification factor of said tube to assure the production of oscillations at said wave length, and a tri-plate condenser having its external plates connected respectively to said grid and anode, and its intermediate plate connected to wave radiating means.

HERBERT SPENCER POLIN.
